UNITED STATES PATENT OFFICE.

HENRY SPENCER LAWSON, OF WEST BERGEN, NEW JERSEY, ASSIGNOR TO
CLARENCE WHITMAN & CO., OF NEW YORK, N. Y.

DESIGN FOR ORNAMENTAL FABRIC.

SPECIFICATION forming part of Design No. 23,887, dated December 25, 1894.

Application filed November 8, 1894. Serial No. 528,262. Term of patent 7 years.

To all whom it may concern:

Be it known that I, HENRY SPENCER LAWSON, a subject of the Queen of Great Britain, residing at West Bergen, in the State of New Jersey, have invented and produced a new and original Design for Ornamented Fabric, of which the following is a specification.

The leading feature of my design consists in a fabric having the ornamentation of essentially the configuration and representation shown in the accompanying drawing and particularly pointed out in the claim.

In the drawing, forming part hereof, which shows a section of fabric exhibiting my design, A is one of the leading figures of my design, consisting of a main or body portion a of the general configuration of a fleur-de-

lis, a stem b extending from the body portion embraced by a collar-like ornament c, and scrolls d d extending from the stem b. 20 This figure is repeated and juxtaposed *ad libitum* and the scrolls d d of one figure A interlock with the scrolls d d of other figures A. Between the figures A are figures B consisting of a multi-angular curvilinear-sided figure e with circles g g and another multi-angular curvilinear companion sided ornament C. 25

What I claim is—

The design for an ornamented fabric substantially as shown and described.

HENRY SPENCER LAWSON.
